No. 18,426.

Patented July 3, 1888.

UNITED STATES PATENT OFFICE.

FREDERICK KOSKUL, OF WILLIAMSPORT, PENNSYLVANIA.

DESIGN FOR THE SURFACE ORNAMENTATION OF WALLS.

SPECIFICATION forming part of Design No. 18,426, dated July 3, 1888.

Application filed March 17, 1888. Serial No. 267,575. Term of patent 14 years.

To all whom it may concern:

Be it known that I, FREDERICK KOSKUL, of Williamsport, Lycoming county, Pennsylvania, have invented and produced a new and original Design for the Surface Ornamentation of Walls, &c., of which the following is a specification.

The accompanying photograph is a plan or face view of my design here shown.

My design consists in the quadrangular elevation A, having beveled or inclined sides B. Upon the face of said elevation A is a ledge, C, and an elevation, D, having a flat upper face, E, and rounded or convex sides L M N O. Parallel to each edge of elevation A A appear three elongated elevations, as F G H, and dis-

posed at each corner of the design between the ends of said elevations F G H is a group of nine rectangular elevations, I. All of these elevations F G H I have beveled or inclined 20 sides, and between all of them appear grooves or channels, as J and K. The outer faces of the elevations F, G, H, and I are flat.

I claim—

The design for surface ornamentation of 25 walls, &c., substantially as herein shown and described.

FREDERICK KOSKUL.
